FUSE

Filed Sept. 2, 1921

UNITED STATES PATENT OFFICE.

ELMER L. OGLE, OF CHICAGO, ILLINOIS, ASSIGNOR TO FEDERAL ELECTRIC COMPANY, OF CHICAGO, ILLINOIS, A CORPORATION OF ILLINOIS.

FUSE.

Application filed September 2, 1921. Serial No. 497,888.

To all whom it may concern:

Be it known that I, ELMER L. OGLE, a citizen of the United States, and a resident of Chicago, county of Cook, and State of Illinois, have invented certain new and useful Improvements in Fuses; and I do hereby declare that the following is a full, clear, and exact description thereof, reference being had to the accompanying drawings, and 10 to letters of reference marked thereon, which form a part of this specification.

This invention relates to an overload circuit breaker or, as it is commonly known, an electric fuse and consists of the matters 15 hereinafter described and more particularly pointed out in the appended claims.

The invention relates especially to the type of fuse described in Letters Patent No. 1,276,800 granted to me on August 27, 20 1918 and its object is to further simplify and perfect fuses of the kind shown therein.

The advantages and novel features of my improved construction will appear as I proceed with my specification.

25 In the drawings:—

Figure 1 is a view representing a longitudinal central section through a fuse embodying the novel features of my invention;

Figure 2 is a transverse section through 30 Fig. 1 in a plane indicated by the line 2—2 of Fig. 1;

Figure 3 is a transverse section through Fig. 1 in a plane indicated by the line 3—3 of Fig. 1;

Figure 4 is an end view of the removable cartridge of the fuse;

Figure 5 represents perspective views of parts of one end of the cartridge as they appear in the process of assembly;

Figure 6 is an end view of the parts shown in Fig. 5 as they appear immediately after assembly but before they have been locked together in the manner presently to be described.

45 Referring now to that embodiment of the invention illustrated in the drawings: 10 indicates the tubular body of the fuse, made of insulating material, and provided at its ends with the metallic ferrules 11, 12. The

50 ferrule 11 is a cap with a closed end and is permanently fixed to the tubular body 10. The ferrule 12 is open at the end so that the cartridge 13 may be inserted into the fuse body, but has a semi-circular, radial, inwardly extending end flange 14, adapted

to engage and overlie the peripheral edge of a closure disc 15 which has a lug 16 extending at right angles to it, by means of which it is secured in place by a screw 17 which is threaded into the ferrule. 60

The features of construction thus far described are substantially as shown in my Letters Patent hereinabove referred to and require no detailed description.

The cartridge body 13 is closed at the 65 right hand end, as in my former patent, by means of a star washer 18, engaged within the tube adjacent its end and by a metallic flanged cap 19 having its flange clinched against the sides of the tube,—both the 70 washer and the head of the cap being slotted to permit the extension through them of the fusible member or bar 20. In order, however, to insure a uniform, definite spacing of the star washer from the end of the 75 tubular body of the cartridge so that it may take a substantial grip against the inside of the tube, I provide a plurality of detents 21 in the head of the cap 19, which are stamped or punched from the metal of said 80 head so as to project inwardly and away from its inner face. In assembling the structure, the star washer 18 is first inserted in the end of the tube and the cap 19 is then applied and its head brought against 85 the end of the tube. This forces the washer within the end of the tube a distance equal to the length the detents 21 project beyond the inner face of the head of the cap, so that when the cap is clinched on the tube, 90 a substantial part of the end of the tube is always gripped between the star washer and the head of the cap.

The opposite end of the cartridge tube is closed by a plug 22 to which end of the 95 fusible member 20 is attached and by a cap 23 clinched on said plug with the end of the cartridge tube gripped between the two. The plug 22 is tapered toward its end (see Figures 1 and 5) where it is provided with an 100 annular flange 24. The plug has an internally threaded aperture 25 extending longitudinally through it to receive a screw 26 extending through the head of the closed ferrule 11 which screw acts to lock the cartridge in position as in my former patent. The inner end of the plug has a tubular extension 27, which has one side collapsed within the opposite side, with the end of the 105 fusible bar gripped between, the parts be- 110

ing soldered together to provide a permanent connection.

The plug 22 has an annular boss 28 at its outer end and the cap 23 has a circular aperture in its head adapted, before assembly, to loosely embrace said boss. The plug 22 has a longitudinally extending notch 29 adapted to be engaged by a pin 30 extending inwardly from the ferrule 11, through the body of the fuse in the usual manner, for preventing rotation of the cartridge while the screw 26 is being screwed into the plug 22. The annular head of the cap 23 is cut away as indicated at 31 at a point corresponding to the location of said slot in the plug. The cap 23, originally cylindrical, is made large enough to slip easily upon the end of the cartridge tube while the plug 22 is designed to fit within the end of said tube. After the two are assembled in this manner, with the cut-away part 31 of the head of the cap, in line with the longitudinal slot 29 in the plug, the side wall 31^a of the cap adjacent the notch 29, is forced into said notch so as to conform as nearly as may be to the cross-section of said notch and the body of the cap is clinched down against the tapered body of the plug,—the end of the tube being gripped between. This causes the aperture in the head to contract and the metal defining said aperture to grip the boss 28 on the outer end of the plug, and thus securely lock the cap and plug on the end of the cartridge tube.

I claim as my invention:

1. In an electric fuse, a cartridge containing a fusible element, said cartridge comprising a tubular body of insulating material, a closure for one end of said body through which said fusible element extends,

a closure and fusible element support for the other end of said body comprising an inwardly tapered, internally threaded, metal plug, provided with an extension for the attachment of the fusible element, and a tubular cap with an apertured head adapted to be clamped upon said plug with the end of said tubular body gripped between, said plug having a boss adapted to extend through the aperture in the head of said cap, said plug having a longitudinal notch and said head being cut away in line with said notch, and the body of the cap extending into said notch so that the metal of the head is closely engaged with the boss on said plug.

2. In a cartridge for an electric fuse, in combination with the tubular body thereof, a closure and fusible element support for one end of said cartridge comprising an inwardly tapered, internally threaded, metal plug having a boss at its outer end and a longitudinal notch on one side, and a tubular metal cap having an apertured head through which said boss extends, the head being cut away in line with the notch in said plug, and the cap being clamped upon said plug with the tubular body of the cartridge between, and with the tubular wall of the cap extending into the notch of the plug.

In testimony that I claim the foregoing as my invention, I affix my signature in the presence of two witnesses, this 15th day of August, A. D. 1921.

ELMER L. OGLE.
